CATHODE

William W. Eitel and Jack McCullough, San Bruno, Calif., assignors to Heintz & Kaufman, Ltd., San Francisco, Calif., a corporation of Nevada

Application April 17, 1934, Serial No. 720,941

2 Claims. (Cl. 250—27.5)

Our invention relates to cathodes for thermionic devices, and particularly to the form of such cathodes.

Among the objects of our invention are: to provide an improved mounting for multiple filaments of thermionic devices; to provide a multiple filament construction which distributes the electron flow therefrom more uniformly over the anode surface; to provide a cathode construction in which the heat drain from portions of the filaments is substantially eliminated; to provide an improved cathode construction which produces relatively greater electron emission than similar cathodes in present use; and to provide a simplified and compacted multiple cathode construction for thermionic devices.

Other objects of our invention will be apparent or will be specifically pointed out in the description forming a part of this specification, but we do not limit ourselves to the embodiment of the invention herein described, as various forms may be adopted within the scope of the claims.

Referring to the drawing:

Figure 1 is a perspective view showing the improved cathode of our invention as incorporated in a space discharge device and showing its relationship to other electrodes mounted therein. Parts of the view are broken away to disclose the construction more clearly.

Figure 2 is a perspective view of the generally practiced method of mounting multiple filaments.

In broad terms, our invention comprises the combination, in an electrical discharge device having, preferably, a substantially tubular anode, a tubular shaped control electrode comprising a plurality of spaced vertically disposed conductors, a cathode support comprising, preferably, a cylindrical standard in axial alignment with the anode and control electrode, and a pair of spaced cathode terminals disposed adjacent the standard, of a cathode comprising a pair of filaments secured to each other, and to a terminal, at the ends thereof, the filaments diverging with respect to each other from the terminals to a point equivalent to substantially half of the length of the filaments, provided with bights at this point, and spaced apart a distance corresponding with the spacing of the terminals, so that the filaments are disposed in angular relationship with each other and are symmetrical in vertical planes displaced ninety degrees about a horizontal plane passing midway between the terminals and the bights.

A great majority of the thermionic tubes de-
55 signed for operation at powers of the order of one

or two kilowatts, are usually provided, due to the heavy currents handled, with a plurality of cathodes or filaments connected together in parallel. An example of such a construction, and one which is extensively used, is illustrated in Figure 2 of the drawing, the inverted V type filaments being indicated by the reference numeral 2. The free ends of the filaments are usually secured to a pair of spreader bars 3 which are welded to the ends of leads 4 supported by the stem 6 of the tube. The shape of these spreader bars varies considerably in different designs of tube, some manufacturers preferring the straight type, as illustrated, and others preferring a U shaped bar. A standard 7, also supported by the stem at a point adjacent the leads 4, extends upwardly and is provided near the top thereof with suitable means for engaging the bights of the filaments, which means may conveniently be a pair of resilient arms 8 for tensioning the filaments and provided with hooked portions 9 for engaging the bights thereof.

It has been observed, under actual working conditions, that when filaments mounted in this fashion are heated, those portions of each filament adjacent the spreader bars, as arbitrarily indicated by the dimension A in Figure 2, will not be raised to the same temperature as the remainder of the filament. This is due to heat drainage from these portions of the filaments by the spreader bars and the terminals. It follows, therefore, that maximum electron emission is not procurable from filaments mounted in the manner described.

Still another detrimental feature of such a construction lies in the fact that due to the close relative spacing of each filament adjacent the bight thereof, that area of the anode nearest the bight will receive a concentrated electron bombardment, while proportionately few electrons will fall on the areas of the anode farthest removed from the bights. In most instances, the power being handled by the tube is such that this bombardment may be of sufficient magnitude to cause serious overheating of the anode in the areas subjected to the concentrated bombardment, with accompanying detrimental effect on the efficient operation of the tube.

We have, by the provision of an improved mounting for multiple filaments, obviated these defects to a considerable degree, by providing for an increase in the electron emission from the cathode, by substantially reducing the heat drain at the attachment points and thereby, by such provision, creating a tube capable of su-
55

5 prior performance. Furthermore, we have caused the filament wires to converge at the attachment points so that one wire will help heat the other. We have also succeeded in distributing 10 the electron emission from the cathode more uniformly over the anode surface which permits greater heat dissipation by this electrode than is possible were it operating with the type of cathode generally used.

10 15 In greater detail, the preferred form of the improved cathode of our invention, and its relationship to other electrodes in a space discharge tube, is shown in Figure 1, in which the stem 6 is provided with the standard 7 and the terminals 4, the standard, at its upper end, being provided with the resilient arms 8 formed with the bightengaging hooks 9. An anode 11 and a control electrode 12 are shown surrounding the cathode.

20 25 The spreader bars 3 of the previously described construction have been dispensed with and the filaments 2 have been brought together at their ends and anchored by welding directly to the ends of the terminals 4. The terminals are preferably spaced apart a distance corresponding to the spacing of the hooks 9 so that each filament is disposed in relation to the other at the same angle as the angle of the legs of each filament between the bight and the terminals thereof. It will thus be seen that the combined filaments are 30 35 symmetrical in vertical planes displaced ninety degrees with a horizontal plane passing midway between the bights and the terminals.

35 Due to the elimination of the spreader bars the heat drain from the anchored ends of the filaments has been greatly reduced, in fact observations of a cathode constructed in this manner, under actual working conditions, failed to disclose a discernable portion of the filaments that was not heated to emission temperature. This, it 40 45 is believed, is due to the heat radiating from the closely adjacent portions of the filaments near the terminals, assisting in raising the temperature of each other to a degree corresponding to other parts of the filaments, and this together with the reduced heat drainage, provided by removal of the spreader bars, causes the filaments to be heated to emission temperature over their entire lengths between the terminals. It is obvious, therefore, that due to the substantial elimination 50 55 of this undesirable heat drainage, the electron emission of the cathode, for a given exciting current, is considerably increased, which increase reflects itself in improved performance of the tube.

55 Another desirable feature, created by the arrangement of the filaments in this manner, is the symmetry of the cathode when it is viewed alternately from each end in positions rotated ninety degrees from each other. This provides, at the filament terminals, a similar condition to that existing at the bights thereof, in that the filaments are in the same spaced relationship at the two

points. Thus the concentration of electron flow from the cathode to the anode 11 is similar at both ends of the latter electrode and, as a result of this, more uniform distribution of electrons is obtained over the surface of the anode and it is 5 capable of dissipating the heat generated more rapidly, consequently the electrode is not likely to be overheated.

Still another desirable feature presents itself in that since the cathode assembly has been compacted, due to the removal of the spreader bars, the diameter of the control electrode 12, and also the anode 11, may be considerably reduced. This may readily be seen by referring to the drawing. The diameter of the smallest cylinder that could 10 be placed about the construction of Figure 2, is slightly greater than the diagonal distance between the ends of opposite spreader bars, while the diameter of a cylinder that would clear the construction of Figure 1, is slightly greater than 20 the distance between the outer surfaces of the terminals. This distance, it will be seen, is considerably less than the diagonal distance referred to in respect to Figure 2. The elimination of the spreader bars and the rearrangement of the filaments are also instrumental in reducing danger of 25 arcing between grid and cathode.

30 The cathode just described permits the production of thermionic tubes possessing a higher degree of efficiency than was heretofore obtained 35 in tubes of this character, permits a reduction in size of the tube elements, and due to its simplicity it may be constructed more economically and expeditiously.

35 We claim:

1. The combination, in an electrical discharge device having an anode, a control electrode and a cathode support contained therein, said support comprising a pair of spaced cathode terminals, a standard disposed adjacent said terminals and resilient arms mounted on said standard, of a cathode comprising a pair of filaments joined together at their free ends and secured to said terminals, said filaments being looped over said resilient arms in spaced relationship, said spacing corresponding to substantially the spacing between the terminals. 40 45

2. The combination, in an electrical discharge device having a plurality of cooperating electrodes mounted therein including a cathode support, of a cathode comprising a plurality of filaments provided with bights substantially midway between their free ends, said bights adapted to be supported by said cathode support, a free end of each filament being secured to a free end of another filament in a plane substantially ninety degrees out of phase with a plane passing through the bights of the filaments. 50 55
